Primary Examiner — Ian Simmons*Assistant Examiner* — Keith Wilson(74) *Attorney, Agent, or Firm* — Assouline & Berlowe, PA; Loren Donald Pearson(57) **CLAIM**

I claim the ornamental design for a meditation seat, as shown and described.

DESCRIPTION

FIG. 1 is a perspective top front left view of the meditation seat;

FIG. 2 is a perspective bottom right rear view thereof;

FIG. 3 is a top view thereof;

FIG. 4 is a bottom view thereof;

FIG. 5 is a right side view thereof, which is a mirror image of the left side view that is not shown;

FIG. 6 is a front view thereof; and,

FIG. 7 is a rear view thereof.

The broken lines shown depict stitching and are part of the claimed design.

1 Claim, 6 Drawing Sheets(56)
